UNITED STATES PATENT OFFICE.

NEWELL T. FOGG, OF MELROSE, MASSACHUSETTS.

BELT.

1,338,859.

Specification of Letters Patent.

Patented May 4, 1920.

Application filed February 24, 1919, Serial No. 278,565. Renewed February 2, 1920. Serial No. 355,697.

To all whom it may concern:

Be it known that I, NEWELL T. FOGG, a citizen of the United States, residing at Melrose, county of Middlesex, Commonwealth 5 of Massachusetts, have invented certain new and useful Improvements in Belts, of which the following is a specification.

This invention relates to belts for personal wear, and particularly to a belt provided 10 with a normally coiled line adapted to be carried on the person and unwound or detached for service as occasion requires.

My invention is especially designed for use by boy scouts and like organizations as part 15 of their standard equipment, and in the further treatment herein, I shall discuss it in connection with a belt of the type worn by boy scouts.

The object of my invention is to provide 20 a belt and line which may be comfortably worn on the person without interfering with free body action and which may be readily uncoiled or detached for service as a life-line, tow-line or for any other purpose where 25 a line may be needed.

My invention consists in the novel construction, arrangement, and relation of parts described in the following specification, illustrated in the accompanying drawings, 30 and particularly pointed out in the appended claims.

Throughout the specification and drawings like reference characters are correspondingly applied, and in the drawings:—

35 Figure 1 is an elevation of a line provided belt in accordance with my invention.

Fig. 2 is a detail view particularly illustrating a simple method of fastening the end of the line to the belt.

40 Fig. 3 is a somewhat diagrammatic view illustrating a simple method of rapidly uncoiling the line, and

Fig. 4 is a view showing the line uncoiled.

For the purposes of this application, I 45 have shown a belt of the type worn by boy scouts as part of their standard equipment. It will be understood of course that this showing is purely illustrative, and that I may apply the principles of my invention 50 to other types of belts.

The illustrated belt consists of a length of webbing 1 having the usual clasp 2 at one end whereby the belt may be adjusted to the body of the wearer, and as here shown, provided 55 near each end with slidable swivel hooks 3

for the convenient suspension of various articles of equipment.

Coiled along the belt in a plurality of close laid parallel turns disposed longitudinally between the suspension hooks 3 is a line 4 of 60 suitable gage and material.

The hooks 3 are attached to the belt by the bands or loops 3¹. These bands are preferably formed of strips bent around the belt and brought up in parallel ears 7 which are 65 fastened together by a tubular rivet 8 through which the ring of the swivel 6 of the hook 3 is passed. The ears 7 are centrally disposed relative to the width of the belt so as to bring the swivel on the longitudinal 70 axis of the belt and line roll.

The ends of the line 4 may be secured to the belt in any convenient manner, as by carrying the line through suitably reinforced spaced holes 5 formed in the belt, 75 knotting the line and looping the free end under a few of the turns of the line, as shown in Fig. 2. If desired, however, one end of the line, preferably the end adjacent the clasp 2 may be permanently attached to 80 the belt, or the line ends may be held by any conveniently detachable clamp.

In Fig. 3, I have illustrated a convenient method of rapidly unwinding the line. By removing the belt from the person and holding it outstretched by means of the swiveled hooks 3, the belt will turn as a reel when the free end of the line is drawn in the direction indicated by the arrow in said figure.

When the device is to be used as a rescue 90 outfit the line is unwound and the belt re-clasped in which condition it may be thrown with accuracy for some distance. The belt not only affords the necessary projective factor by its form and weight, but is a convenient loop or sling through which the hand, arm or shoulder may be thrust.

95 The line 4 furthermore combines in a peculiar manner with the belt 1 by reason of the spaced eyeletted holes 5. These eyelets 100 are of a size adapted to receive with a close fit the line 4.

105 By lacing the line 4 through a plurality of these holes and holding the belt taut, a frictional bind is effected by which a load either animate or inanimate may be eased off or lowered. The belt in this use may be strapped around the person or grasped in the hands, who with the free end attached to some stationary object might for example 110

lower himself from a window in case of fire. In this use the line 4 is permitted to feed frictionally through the eyelets of the belt being held by reason of the slant of the line 5 in making the turn through each eyelet. By varying the number of eyelets through which the line is passed, the degree of friction may be adjusted. A scout trained with this belt would know in advance approximately the degree of friction added by each 10 additional hole. For lowering a load from above the object is attached to the free end and the line fed through the tightly stretched belt as a grip. In such a case the belt might be put around either the body or a tree trunk or other object by which the belt would be held taut.

Various modifications in the form and construction of my device may obviously be 20 resorted to if within the limits of the appended claims.

What I therefore claim and desire to secure by Letters Patent is:—

1. As an article of personal wear, a life 25 saving device consisting of a belt adapted to be normally worn about the body and removable therefrom and adapted to be hurled through the air as a loop-form hand-hold or life preserver, and a life line secured at one 30 end to the belt and wound thereon in a plurality of close-laid turns progressively incasing the belt and conforming thereto whereby to permit the belt to be comfortably applied about the body, the free end of the 35 line being held in the hand when the line is unwound and the belt removed from the body and hurled through the air.

2. A belt of the class described comprising a belt member and a relatively small line 40 wound thereon in a plurality of closely-laid

turns progressively incasing the belt and conforming thereto, said belt having a plurality of openings of size to snugly receive the line when laced therethrough said openings being distributed longitudinally along 45 said belt at intervals spaced for frictional feed of said line.

3. A belt for personal wear having a pair of suspension hooks swiveled thereon near the ends thereof, and a line wound on the 50 belt between said hooks in a plurality of closely-laid turns and adapted to be unwound by a pull applied transversely to the longitudinal axis of the belt, the belt rotating between said swiveled hooks as the line 55 is unwound therefrom.

4. A belt for personal wear having a pair of suspension hooks swiveled thereon on substantially the median line thereof and near the ends of said belt, and a line wound on 60 the belt between said hooks in a plurality of closely-laid turns and adapted to be unwound by a pull applied transversely to the longitudinal axis of the belt, the belt rotating between said swiveled hooks as the line 65 is unwound therefrom.

5. An article of the class described comprising a line member laid in a plurality of flattened successive close laid unattached turns and forming a flattened tubular elongated body, and a flat belt core having belt 70 fastenings projecting beyond the ends of said line member, said line member and said belt core being separable.

In testimony whereof I affix my signature 75 in presence of two witnesses.

NEWELL T. FOGG.
